UNITED STATES PATENT OFFICE.

EDWARD J. DEEGAN AND WILLIAM HODGSON, OF NEW YORK, N. Y.

REGULATOR.

1,254,888.

Specification of Letters Patent.

Patented Jan. 29, 1918.

Application filed April 22, 1916. Serial No. 92,967.

To all whom it may concern:

Be it known that we, EDWARD J. DEEGAN and WILLIAM HODGSON, citizens of the United States of America, residing at the city of New York, in the county of Bronx and State of New York, have invented certain new and useful Improvements in Regulators, of which the following is a specification.

10 Our invention relates to thermostatic regulators and particularly to a regulator of such character as to be adapted to regulate the flow of gas to radiators, heaters, or other devices, in the use of which it is desired to 15 reduce the flow of gas when the heat of the surrounding air rises above a predetermined temperature.

Figure 1. is a plan or face view of a regulator embodying our invention.

20 Fig. 2. is a sectional view of said device.

Fig. 3. is a plan view of the same, representing the side of the base opposite to that shown in Fig. 1.

25 Fig. 4. is a central, vertical, sectional view through the regulator.

1 represents a base, preferably a brass casting, the part 2 being in the form of a flanged circular disk and the part 3, preferably integral with 2, in the form of a tube 30 extending across said disk, preferably on a diametric line.

This tube is provided with ports 4, 5, usually screw threaded to permit convenient attachment to gas pipes or other forms of 35 conduits.

The aperture from port 4 to port 5, is interrupted by a wall 6, usually about midway between them, and through the side walls of the respective sections of said tube which, 40 as shown, are also parts of the disk 2, there are openings 7, on one side of the wall 6, and 8—12, on the other side of the wall, though we do not limit ourselves to a single opening or a plurality of openings on either 45 side of said wall. A minor aperture 13, through wall 6, may be provided.

The outer faces of the walls of these apertures are finished smoothly to constitute valve seats for the valve which is provided 50 for closing them.

Seated on the disk 2 and fitting neatly within the circular flange at its edge there is a cover, 14, preferably a convex brass casting, and between said cover and the disk 2, 55 we seat a flexible diaphragm 15, its edge be-

ing secured tightly to the cover and both to the base 2.

A quantity of volatile fluid (which may be ether) is placed in the inclosure formed by cover 14 and diaphragm 15 and hermetically sealed therein.

It will be noticed that this device presents a considerable surface to the action of the surrounding air, for instance that of a room containing a gas radiator connected to the pipe to which the regulator is attached, and that as the tube and the base is preferably one piece, and the cover forms one wall of the inclosure holding the volatile liquid, changes of temperature will be quickly transmitted to that liquid.

The regulator forms a conduit from a section of tubing leading from the gas supply to another section leading to the radiator, and all gas supplied to the radiator must pass through the regulator. Any change in the capacity of the passage will immediately change the flow of gas through it to the radiator.

Now the quantity of volatile fluid having 80 been proportioned to the size of the inclosure and the space the diaphragm must move to interrupt the flow of gas at a given temperature, say 70, the gas is turned on and the radiator is lighted.

As soon as the temperature of the room rises, that temperature will be transmitted, particularly through cover wall 14, to the volatile fluid and that will begin to expand and to force the diaphragm 15, which constitutes a valve, toward the valve seats surrounding apertures 7—12, thereby reducing the flow of gas.

When the temperature reaches the predetermined figure—say 70, the diaphragm 95 valve will rest upon the valve seats and shut off the flow of gas altogether, if it be arranged, as shown, to accommodate that desire. If the aperture 13 be provided, a small quantity may pass through it to maintain a pilot flame at the radiator, or the parts and the volatile fluid may be so proportioned that a temperature of 70 will not absolutely close the normal conduit, but will merely reduce its capacity to such a degree 105 as to merely furnish sufficient gas to maintain said pilot flame. As soon as the temperature lowers, whatever the cause, the fluid will contract, the diaphragm recede and the passage may enlarge.

2
We prefer to make the apertures plural, as shown at 8-12 for the reason that such construction, aids in preventing the diaphragm from bulging so as to lose its resilient character and become useless, and also acts as a strainer, a series of small apertures being less likely to pass foreign matter than one large one.

We also prefer to arrange the apertures on the different sides of the wall at even distances from the center of the diaphragm, when it is desired to seat it upon the surface surrounding all of the apertures, since an even seating is thus best secured. In short, that the valve seat, as a whole, shall be concentric, as it were, with the diaphragm outline, but we do not need to close passage 8-12 and also 7. If the diaphragm valve closes the passage or passages through the side wall on one side of the dividing wall, that answers the purpose, which, as noted, is the interference with the flow of gas to its place of use.

What we claim and desire to secure by Letters-Patent, is:—

1. A regulator of the character designated for interposition in a gas supply conduit, comprising a coupling section in the form of a pipe adapted for direct engagement with sections of said gas supply conduit, said coupling pipe section being formed with an internal perforate partition disposed transversely of the length and dividing it into a main pressure chamber and an attenuated pressure chamber, with lateral ports on either side of said partition opening into a diaphragm chamber, said diaphragm chamber, an elastic resilient imperforate diaphragm hermetically sealed there-

40 in and adapted to control the auxiliary flow of gas through said lateral ports to the attenuation chamber, and a volatile fluid in-

terposed between said diaphragm and the outer wall of said diaphragm chamber, whereby a constant minimum gas supply to the attenuated pressure chamber is afforded by the perforate partition supplemented by an auxiliary supply thereto through the lateral ports controlled by the diaphragm, for the purpose set forth. 45

2. A regulator of the character designated for interposition in a gas supply conduit, comprising a cylindrical coupling section in the form of a pipe adapted for direct engagement with sections of said gas supply conduit, said cylindrical coupling pipe section being formed with an internal perforate partition disposed transversely of the length of and dividing it into a main pressure chamber with lateral ports on either side 60 of said perforate partition opening into a circular diaphragm chamber integral with the said cylindrical coupling pipe section and an attenuation chamber, said diaphragm chamber and a circular elastic resilient 65 imperforate diaphragm hermetically sealed therein and adapted to act as a valve to control the auxiliary flow to gas through said lateral ports to the attenuation chamber, and a volatile fluid interposed between 70 said diaphragm and the outer wall of said diaphragm chamber, whereby a constant minimum gas supply to the attenuated pressure chamber is afforded by the perforate partition supplemented by an auxiliary supply thereto through the lateral ports controlled by the diaphragm, for the purpose 75 set forth.

In testimony whereof, we have signed our names to this specification this 17th day of April, 1916.

EDWARD J. DEEGAN.
WILLIAM HODGSON.
